UNITED STATES PATENT OFFICE.

SAMUEL C. BARR, OF CHILLICOTHE, OHIO, ASSIGNOR TO THE BARR COMPANY, A CORPORATION OF OHIO.

VENDING-MACHINE.

1,282,727.

Specification of Letters Patent. Patented Oct. 29, 1918.

Application filed November 27, 1916. Serial No. 133,546.

To all whom it may concern:

Be it known that I, SAMUEL C. BARR, a citizen of the United States, residing at Chillicothe, in the county of Ross and State 5 of Ohio, have invented certain new and useful Improvements in Vending-Machines, of which the following is a specification.

This invention relates to vending machines and is designed particularly as a machine whereby a person may test his eyes and obtain the desired lenses by the manipulation of certain elements in connection with the dispensing mechanism.

In this connection, my invention resides 15 essentially in the combination of a test lens holding means provided with a plurality of test lenses of varying properties; with mechanism for holding and dispensing for-sale lenses which have the same property as 20 signified by the testing lens. My invention also resides in the different types of structures embodied in the above features for carrying forth the objects sought.

A further object of the invention resides 25 in means whereby the patron may test his eyes as to various focal lengths and also may test them as to distance and, after the proper lens has been determined, obtain the desired lenses by the proper manipulation 30 of the dispensing mechanism.

Still a further object of the invention resides in a means whereby only one eye may be tested, if desired, thereby enabling the patron to determine whether both eyes 35 are defective in the same manner or not, and thereby obtain the different correction for either eye.

The preferred embodiment of my invention is shown in the accompanying sheets of 40 drawings, in which similar characters of reference designate corresponding parts, and in which:

Figure 1 is a front view of my improved type of vending machine,

Fig. 2 is a central vertical longitudinal section of the structure shown in Fig. 1,

Fig. 3 is a horizontal section taken on line 3—3 of Fig. 2,

Fig. 4 is a fragmentary section taken on 50 line 4—4 of Fig. 3 and looking in the direction of the arrows,

Fig. 5 is an enlarged view of a portion of the coin controlled mechanism.

Fig. 6 is a plan view of the structure 55 shown in Fig. 5,

Fig. 7 is a horizontal section represented by line 7—7 of Fig. 2,

Fig. 8 is a side view of the mechanism for adjusting the tester card,

Fig. 9 is a section taken on line 9—9 of 60 Fig. 8,

Fig. 10 is an enlarged section taken on line 10—10 of Fig. 2,

Fig. 11 is a vertical section through one of the disks shown at the right of Fig. 1 65 and represented by line 11—11 of Fig. 1, and,

Fig. 12 is a detail view of a portion of the for-sale lens carrier illustrating the specific construction of one of the compartments. 70

The entire structure is preferably mounted within the interior of a casing 1, whose top, two sides and rear end are preferably made of glass, as is shown, and suitably assembled to present a rigid construction. 75 The front wall 2 is preferably of metal construction and carries a pair of supporting disks 3, which disks are each provided with a plurality of openings 4 in which the test lenses are suitably supported. These test 80 lenses are all of varying properties and the two disks are each provided with a series of gear teeth 5 so that rotation of one will cause a corresponding rotation of the other to successively present pair of lenses of different properties, whereby the patron may 85 test his own eyes. The structure for supporting these disks is best shown in Fig. 11, in which it will be seen that the front wall 2 is provided with a stud 6 upon which 90 the sleeve 7 is rotatably mounted. To each of these sleeves, the respective disks 3 are rigidly secured and on the outside end of the sleeve upon which the disk shown to the right of Fig. 1 is mounted, there is provided 95 a knob 8 so that the user may readily turn the same. Each disk is also provided with a cover plate 9 secured in position in any desired manner and which cover plate is in turn provided with an eye opening 10 arranged side by side as is shown and it is through these openings 10 that the patron must look. The cover plate 9 shown to the right of Fig. 1 is also provided with an index dial 11 which, in the present case, is 100 numbered from 1 to 12, which is the number of test lenses to be found in each of the disks 3. Should the patron desire to test only one eye at one time, the cover plate 12 may be 105 swung to a position to cover either of the 110

openings 10, since this cover plate is pivotally mounted at its lower end, as shown at 13. In this manner, both eyes may be tested, but this test may not necessarily be 5 simultaneous. It will, therefore, appear that as the knob 8 is turned, successive pairs of lenses are presented beneath the openings 10 and if these test lenses are all of different properties, the patron may very 10 readily determine which set suits his eyes best.

In direct testing alignment with the openings 10 and within the cabinet 1 there is mounted a testing card 14, which testing 15 card is designed to be adjusted either forward or backward to present different focal lengths, as may meet the requirements of the patron. To accomplish this, I have mounted the card 14 upon a hinge member 20 15 at its lower end and this hinge member is in turn hingedly mounted to a base 16, this latter being in rigid connection with the rack shown at 17. The rack is in slid- 25 able engagement with a guideway 18 in the guide member 19, which latter extends from the front wall of the casing rearwardly. The rack 17 is designed to be moved back and forth within the guideway 18 and in this manner the card 14 is moved toward or 30 away from the particular lenses which happen to be in back of the openings 10. In order to accomplish this adjustment, the underside of the guide member 19 is slotted as shown at 20 and in this slotted portion 35 the pinion 21 is designed to operate. This pinion is in engagement with the rack bar 17 and is mounted upon a shaft 22 which extends laterally, as best shown in Figs. 9 and 8 and is journaled at its outer end in 40 an upstanding standard 23. The end be- 45 yond the standard 23 is also provided with a pinion 24 and this latter is designed to operate in conjunction with a segmental rack 25 pivotally mounted to the standard 23, as shown at 26. This segmental rack is in turn pivotally connected at 27 with a link 28 the other end of which link is in turn pivotally mounted at 29 in connection with the push rod 30 whose head portion 31- 50 projects beyond the front wall of the cas- 55 ing. Thus, by pulling on the portion 31, the segmental rack 25 will cause a rotation of the shaft 22 by means of the pinion 24 and this in turn causes the pinion 21 to be rotated to move the rack 17 back and forth in its guideway 18.

Should the patron desire a test for distance, means are provided whereby the tester card 14 is withdrawn from view and 60 inasmuch as the rear of the cabinet is made of glass, a similar card may be placed in a remote position in testing alignment with the testing lenses, or an arrangement of mirrors may be resorted to. In the present 65 instance, the hinge member 15 of the testing

card 14 is provided with a depending finger 32 projecting beneath the hinge portion and in such position as to engage the roller 33 mounted on a stud 34 on the rear end of the guide member 19. The card 14 is itself nor- 70 mally held in upright position by means of the spring 35, but when the plunger 30 is pulled out a sufficient distance, the indicator card will have moved rearwardly a distance to bring the finger 32 into engagement with the roller 33. Continued movement then causes the card 34 to turn down against the pressure of a spring 35, thus removing it from interference, for a distance test.

Within the cabinet there is rotatably mounted a cage member or for-sale lens carrier 36 provided with a double row of compartments 37. Each row of compartments corresponds in number with the number of test lenses on each disk and the present in- 80 vention is designed to dispense either spec- 85 tacles or eye glasses, one of which is carried in the upper series of compartments and the other of which is carried in the lower series of compartments. This cage member 90 is rigidly mounted upon the central shaft 38 rigidly secured at its upper end as shown at 39 to the guide member 19 and seated within the socket member 40 at its lower end. The cage is formed of a plurality of 95 horizontal plates or disks 41, 42 and 43 and the lower disk 43 is provided with a flange fitting 44 onto which the pinion 45 is rig- 100 idly connected. Thus, it will appear that rotation of the pinion 45 will cause a cor- 105 responding rotation of the cage 36. This rotation is accomplished in the following manner: Rotatably mounted upon a stub shaft 46 adjacent the base of the cabinet is a gear wheel 47, which meshes with the 110 pinion 45 and which also meshes with the rack bar shown at 48. This rack bar is in turn slidably mounted in a track member 49, which is slotted to accommodate the portion 50 of the rack bar. The rear side of this 115 rack bar is provided with a pair of laterally projecting flanges 51 and the portion 50 is provided with a pair of clips 52 so that while the rack is slidably mounted within the slide member 49, it is also removably 120 mounted therein. Projecting rearwardly from the base 51 of the rack is a hinge por- 125 tion 53 which projects through the front wall 2 of the casing and pivotally carries a latch member 54. This latch member is 120 designed to operate against the tension of the spring 55 and also co-operates with the notched bar 56 mounted on the front 2 of the casing. This bar 56 is provided with a series of notches corresponding with the 125 compartments in the cage 36 and also with the number of test lenses in each of the disks 3.

The manner of operating the structure thus far described is as follows: The knob 130

8 is grasped and as the patient looks through the openings 10 on to the tester card 14, a succession of lenses of different types or characters are presented for view. When 5 the most desirable has been reached, the patron takes note of the position of the arm 57 carried by the knob 8. It will be noted by particular reference to Fig. 11 that this arm 57 is rigid with the knob 8 and carries 10 a socketed portion 58 at its lower end. Within the socketed portion there operates a plunger 59 which is normally forced outwardly by means of the coiled spring 60. This plunger, therefore, resiliently seats 15 itself in any of the sockets 61 on the dial plate 11 as the knob 8 is turned. When the desired lenses appear through the openings 10, the patron takes note of the number on the dial 11 over which the arm 57 appears. 20 In Fig. 1, this arm is shown as being over the number 7. The operator then grasps the handle 53 and unlatches the same by depression on the outer end of the latch 54 and moves it laterally until this latch member 25 comes into engagement with the notch on the bar 56 which corresponds with the number 7. This movement has moved the rack member 48 laterally and this movement has been transmitted to the cage 36 30 by means of the gear 47 and pinion 45 so that the compartments 37 in the cage 36 which contain the spectacles or eye glasses having lenses of similar properties to those of number 7, have been moved to a position 35 of ready coöperation with the dispensing mechanism to be presently described. During the operation of testing the eyes for the most desirable type of lenses, the patron may also adjust the tester card 14 to suit his 40 desires. To do this, the knob 31 is pulled or pushed as may be desired, which correspondingly moves the tester card through the link connection 28, segmental gear 25, pinion 24, shaft 22, pinion 21 and rack bar 45 17. To obtain a distance adjustment, the knob 31 is pulled completely outward, which causes the tester card 14 to assume a horizontal position against the tension of the spring 25 by bringing the finger 32 into engagement with the roller 33.

Three horizontal plates 41, 42 and 43 are held spaced from each other by the spacing rods 43^a. Each compartment plate is bent as shown at 62, 63, 64, 65 and 66. It will 55 be noted that the ends of the portions 66 are spaced somewhat from the sides 64 of the adjacent compartment to give an opening space 67 through which the boxes 68 are designed to be ejected. Each compartment 60 is further provided with a pair of springs 69 shaped as shown, and rigidly secured at one end to the walls 62. As shown in the drawings, each compartment is designed to hold three boxes 68 in which the glasses are 65 packed. When one box has been ejected the

springs 69 serve to force the remaining two laterally, so that one of them is in a position to be ejected on the next operation.

The dispensing mechanism is preferably coin controlled and because of the two series 70 of compartments, one for eye glasses and the other for spectacles, two coin slots 70 have been provided. Referring to Fig. 4, which is a face view of the inside of the front plate 2, it will be noted that a coin 75 chute 71 is provided for each coin opening 70. A latch member 72 is also pivotally mounted, as shown at 73, so that its rear end lies in the path taken by the coin after it has been deposited. Each of these latch 80 members is so proportioned and counter-weighted that when the coin has been dropped thereon, the rear end is depressed under the weight of the coin and this coin then passes down the chute 71 toward the 85 money drawer.

After the coin has been deposited, either of the plungers 74 designated specs and eye glasses in Fig. 1, is pushed. These plungers are normally held locked by the front ends 90 75 of the levers 72, by seating themselves in the vertical cut-out portion 76. The inner wall of each of these slots 76 terminate short of the other to present a rearwardly extending incline 77 and the weight of the coin 95 previously inserted, is sufficient to elevate the end 75 of the proper latch lever 72 to a position of release out of the slot 76. In this position, the lever is stopped by one of the springs shown at 78, but a push upon 100 the plunger 74 causes the weighted end 75 of this lever to ride the incline 77 against the tension of the spring 78. In order to insure the proper operation of the dispensing mechanism, it is essential that whichever plunger 74 is operated, it shall move its full distance before it returns. For this reason, a portion of the plunger is provided with a series of teeth 79 which coöperate with the dog 80 pivotally supported to the 105 casing framework, as shown at 81. This dog is held in the position shown in Fig. 5 by means of the tension spring 82 so that inward movement of the plunger 74 causes the dog to tilt slightly to come into abutting 110 engagement with the teeth 79. Return movement of the plunger is then impossible until it has been pushed its full distance to move the cut-out portion 83 to a position beneath the depending portion of the dog 120 to allow it to reverse its movement.

The inner end of each plunger 74 is provided with an upstanding arm 84 onto which a pair of spring fingers 85 are secured. Reference to Fig. 3 will show that these 125 spring fingers 85 are provided with a hook 86 on their ends and are shaped to enter through the openings 67 of the compartments when the cage has been properly positioned. Therefore, during the time that 130

the plunger is being pushed in, the fingers 85 also move inwardly in the space between the plates forming the various compartments and directly beneath the entrance portions designated 67. When the stroke has been completed, the hook portion 86 will have come into engagement with the rear side of the box and return movement will then cause this box to be withdrawn and 10 passed into the chute 87. This chute 87 extends down through the floor of the cabinet into the space 88 from whence the patron may remove his purchase. It will be noted that the gear wheel 47 is provided with 15 spokes on its inner side only, so as to permit this chute 87 to pass through the base of the cabinet without interference from the gear wheel itself. Also, in Fig. 2, there is shown a deflector plate 89, which prevents 20 the boxes from the upper series of compartments from catching on any of the projections forming the dispensing mechanism for the lower series of compartments.

Thus, it will be apparent, that upon desiring 25 a pair of glasses, the patron first tests his eyes by turning the knob 8 until he ascertains the proper lens number. The handle 53 and latch 54 are then operated to bring the latch structure into engagement 30 with the notch on the bar 56 which corresponds with this number. The patron next decides whether he desires eye glasses or specs and drops his coin in the corresponding coin opening 70. After having done 35 this, the proper plunger 74 is pushed, whereby the spring fingers 85 come into engagement with the box containing the glasses and return movement of this plunger causes 40 its ejection. It will be readily understood that any desired number of compartments, sections and coin deposit places may be used but, for the sake of convenience, I have only shown two sections and coin deposit places 45 and twelve compartments.

45 What I claim, is:

1. In a vending machine of the character described, the combination with a casing, of a shaft rotatably mounted within said casing, a cage structure rotatable with said shaft and including a plurality of article receiving compartments, a discharge chute, rack and gear mechanism for selectively alining any one of said compartments with 50 said discharge chute, and article ejecting means embodying a coin controlled plunger having hooked extremities, said extremities being movable into engagement with an article positioned in a compartment to discharge same into said chute.

60 2. In a vending machine of the character described, the combination with a casing, of

a rotatably mounted cage structure positioned within said casing including a plurality of concentrically arranged article receiving compartments, an article discharge chute, gear and rack mechanism coöperative with said structure to selectively revolve the compartments of the latter into registration with said chute, means of ejecting an article from a compartment into said chute, said means including a slideable plunger, a coin controlled catch for normally locking said plunger against inward movement, and a hooked element carried by said plunger for engagement with a compartment carried article for discharging the latter into said chute upon the reciprocation of said plunger.

3. In a vending machine, the combination with a casing of an article containing structure rotatably mounted within said casing, a discharge chute, means for revolving said structure to selected positions, including a pinion fixed to the axis of said structure, a gear meshing with said pinion, a slideably supported toothed rack engaging with said gear, an arm secured to said rack and extending through a slot formed in said casing, a stationarily supported recessed bar, a locking lever pivotally carried by the outer end of said arm and engageable with the recesses of said bar, whereby upon the movement of said arm said structure will be revolved to selective chute alining position and maintained therein, and coin controlled plunger mechanism for discharging articles from said structure into said chute.

4. In a vending machine of the character described, the combination with a casing, of a rotatably mounted cage structure positioned within said casing and including a plurality of concentrically arranged article receiving compartments, a discharge chute, gear and rack mechanism for selectively revolving said compartments into operative alignment with said chute, means for ejecting an article from said selected compartment into said chute, said means consisting of a coin controlled plunger, resilient means engageable with teeth formed upon said plunger to permit of the partial actuation thereof, and hooked elements carried by the inner extremities of said plunger and operable to engage an article positioned within 100 said selected compartment to eject the same into said chute, substantially as set forth.

In testimony whereof I affix my signature in presence of two witnesses.

SAMUEL C. BARR.
